TOY DEVICE FOR MANIPULATING SIMULATED LOGS BY MEANS OF A SLING CORD AND PULLEYS

Albert L. Snowman, Rte. 2, Arkport, N.Y.
Filed July 25, 1962, Ser. No. 212,248
2 Claims. (Cl. 46—40)

This invention relates to toys and more particularly to a toy in which elements thereof are to be manipulated by the user in simulation of some of the actual operations performed in large-scale commercial logging enterprises.

The primary object of the present invention is to provide a novel and interesting toy for use by children which will be entertaining and require a certain amount of imagination and manipulative co-ordination.

Another object of the invention is to provide a toy as aforesaid which may be safely used by children and which is very rugged and durable.

Other objects and advantages of the present invention will appear from the detailed description hereinbelow and the accompanying drawings wherein:

FIG. 1 is a side elevational view of the device of the invention;

FIG. 2 is a front elevational view of the device of FIG. 1;

FIG. 3 is a fragmentary sectional view on enlarged scale taken substantially along line 3—3 of FIG. 1 to show a detail of construction;

FIG. 4 is a fragmentary sectional view on enlarged scale taken substantially along line 4—4 of FIG. 1 showing another detail of construction;

FIG. 5 is a view on enlarged scale partially in section taken substantially along line 5—5 of FIG. 1; and

FIGS. 6 through 12 are perspective views of various components of the toy of the invention to show details of construction.

Broadly speaking, the toy of the invention is designed to enable the user to simulate the stacking of newly cut logs for storage through the winter months as is the practice in a number of logging areas.

In the specific embodiment of the toy of the invention described herein I use log members 20 which are represented by smoothly finished dowels. A base member 22 is made up of a pair of cross ties 23 to which are fastened, as by nails or screws, a pair of generally parallel supporting members 24, 24. The base member is designed to support a gin pole 30 and for this purpose an upper cross tie member 25 is mounted to the tops of the supports 24, 24 overlying one of the cross ties 23 as best seen in FIG. 6. The cross tie 25 is provided with a bore 26 and a corresponding bore 27 is provided in the lower tie member 23 along the same axis as the bore 26 but of a smaller diameter for purposes explained hereinbelow. The base member is designed to support the bottom-most layer of a series of stacked logs and, for purposes of easier manipulation, a pair of log members 20, 20 are fixedly mounted on the front and back ends of the supports 24, 24. In the present embodiment, the logs are fixed by countersunk screws 28, 28 but any preferred means of attachment may be utilized for this purpose.

The gin pole 30 has its lower end turned down to a reduced diameter portion 31 which provides a shoulder 32 (FIG. 10). The pole is dimensioned so that it will slip fit through bore 26 and the reduced portion 31 will fit into bore 27. The shoulder portion 32 provides a stop. For convenience in packaging and storing, I fabricate the gin pole in two sections, the lower section 30 as described and the upper section 30a which has its lower end formed with a reduced dowel portion to slide into a

2

bore provided in the upper end of the gin pole 30 in known manner, illustrated in FIG. 5.

A series of rack members 34 are provided to support successive layers of the logs that have been stacked in place and each rack consists of a pair of cross supports 24, 24 and, similar to the base member construction, each rack has log members 20 affixed to span the front and back ends of the members 24. Added rigidity may be gained by the use of a dowel 35 which connects the cross members 24, 24 intermediately of their ends (FIG. 7).

A ramp 40 is constructed of a pair of stringers 42, 42 which are joined by dowels 43, 43. The upper ends of the stringers 42, 42 are radiused as indicated at 44 to fit over log members 20 to help maintain placement of the ramp while being used, as will be explained hereinbelow.

The toy is complete by provision of two handling-line members 46 and 47, each of which has a hook 48 affixed to each end thereof. Pulleys for the handling lines are provided at the top of the gin pole 30 as indicated at 50 and fastened to the base member as indicated at 51. These are preferably conventional swivelable pulleys and may be attached as by staples 52, 52.

In use, the gin pole is set up in the base member and the handling line 47 has its opposite ends attached to the front log by engaging the hooks 48, 48 with eyes 54, 54 which are provided adjacent the opposite ends of each of the logs 20 which are affixed to the front ends of the base 22 and each of the rack members 34. The line 46 is run through each of the pulleys 50, 51 and one end thereof is hooked to the approximate center of the line 47. (See FIG. 2.)

The ramp is placed with the radiused portions 44, 44 engaging the front log of the base member 22. The user then may place a log member 20 in the cradle formed by the line 47 as shown in FIGS. 1 and 2. Pulling on the unattached end of the line 46 will then cause the log 20 to be rolled upwardly along the ramp 40 and to fall onto the base member. This may be continued until the row of logs is completed. The rack member 34 is then placed atop the row of logs, the ramp is positioned with its end over the front log of the rack and the operation of rolling the logs up the ramp may then be resumed.

Although only one form of the toy of the invention has been shown and described in detail, it will be appreciated that changes and modifications may be made therein without departing from the spirit of the invention or the scope of the appended claims.

I claim:

1. A toy, comprising a base member including parallel bottom ties and transversely disposed cross members, a top tie spanning said cross members in spaced overlying relation to and paired with one of said bottom ties, said paired ties being bored in mutual alignment to provide a two-part gin pole step, a gin pole fitted into said step, a first toy log fixed to said cross members to lie alongside said top tie, a second toy log fixed to the opposite ends of said cross members in parallel spaced relation to said first toy log thereby providing a crib space between said fixed logs to receive therebetween a group of loose toy logs, said second toy log having a pair of relatively spaced eye devices extending laterally therefrom, a ramp device comprising a pair of stringers interconnected in parallel relation and having hook-shaped end portions whereby to lodge the upper end of said ramp upon said second fixed toy log, a flexible sling cord having hooks at its opposite ends adapted to engage said eye devices respectively, and a hoist cord having a hook at one end for detachable engagement with a mid portion of said sling cord and training through a pulley at the top of said gin

pole and thence down and around a pulley at the base of said gin pole.

2. A toy, comprising a base member including parallel bottom ties and transversely disposed cross members, a top tie spanning said cross members in spaced overlying relation to and paired with one of said bottom ties, said paired ties being bored in mutual alignment to provide a two-part gin pole step, a gin pole fitted into said step, a first toy log fixed to said cross members to lie alongside said top tie, a second toy log fixed to the opposite ends of said cross members in parallel spaced relation to said first toy log thereby providing a crib space between said fixed logs to receive therebetween a group of loose toy logs, said second toy log having a pair of relatively spaced eye devices extending laterally therefrom, a ramp device comprising a pair of stringers interconnected in parallel relation and having hook-shaped end portions whereby to lodge the upper end of said ramp upon said second fixed toy log, a flexible sling cord having hooks at its opposite ends adapted to engage said eye devices respectively, a hoist cord having a hook at one end for

5 detachable engagement with a mid portion of said sling cord and training through a pulley at the top of said gin pole and thence down and around a pulley at the base of said gin pole, and a series of supplemental crib devices each comprising a pair of parallel spaced cross supports transversely spanned and interconnected by a pair of spaced parallel toy logs, whereby said supplemental crib devices may be successively stacked upon 10 said first fixed toy logs to provide a vertical succession of additional crib spaces for racking a series of loose toy logs into said crib spaces by use of said hoist cord and sling cord.
